US00D667730S

(12) **United States Design Patent**
Toh et al.

(10) **Patent No.:** **US D667,730 S**
(45) **Date of Patent:** **** Sep. 25, 2012**

(54) **CONTAINER**

(75) Inventors: **Kiat-Cheong Toh**, Forest Hills, NY (US); **Simon Nicholas Dutton**, New City, NY (US)

(73) Assignee: **Colgate-Palmolive Company**, New York, NY (US)

(**) Term: **14 Years**

(21) Appl. No.: **29/378,556**

(22) Filed: **Nov. 5, 2010**

(51) LOC (9) Cl. **09-01**

(52) U.S. Cl. **D9/538**; D9/539; D9/552; D9/553; D9/558

(58) Field of Classification Search D9/682, D9/688, 690, 692, 694, 500, 504, 516, 520, D9/529, 537-543, 545-546, 549, 552-553, D9/556, 558, 565-566; 215/382-384; 220/660, 220/669, 675

See application file for complete search history.

(57) **CLAIM**

The ornamental design for a container, as shown and described.

DESCRIPTION

FIG. 1 is a top, front, and left side perspective view of a container showing our new design;

FIG. 2 is a bottom, rear, and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings are for the purpose of illustrating environmental structure and form no part of the claimed design.

1 Claim, 4 Drawing Sheets
